COVERED COAT HANGER

Irma S. Walsh, Washington, D. C.

Application July 1, 1957, Serial No. 46,779

Term of patent 7 years

(Cl. D80—8)

Fig. 1 is a side elevational view of a covered coat hanger showing my new design, the conventional knitted cover thereof being schematically shown.

Fig. 2 is a slightly enlarged sectional view taken on the line 2—2 of Fig. 1, and

Fig. 3 is an enlarged detail of one of the ornaments.

The side opposite that shown in Fig. 1 is the same as that illustrated except for the omission of the ornaments.

The characteristic features of my design for the covered coat hanger disclosed reside in the bead and strand ornaments arranged on one face as shown.

I claim:

The ornamental design for a covered coat hanger, as shown and described.
